AIR CONDITIONING APPARATUS

Frank C. Seeger, Wauwatosa, Wis.

Application May 2, 1938, Serial No. 205,579

2 Claims. (Cl. 62—131)

My invention relates to new and improved air conditioning apparatus for conditioning the air in rooms, entire buildings, boats and other desirable places.

One of the principal objects of my invention is to provide an air conditioning apparatus wherein the parts are so constructed and arranged to form a compact unitary structure.

Another object of my invention is to provide an apparatus of the above described character which is simple in construction, durable in use, and economical in manufacture.

Other objects and advantages will be apparent from the following description, appended claims and annexed drawing.

Referring to the drawing wherein like reference characters designate like parts throughout the several views:

Figure 1 is a top plan view of my invention, the cover thereof being broken away to more clearly illustrate certain parts contained therein.

Figure 2 is a sectional view taken on the line 2—2 of Figure 1.

Figure 3 is a sectional view taken on the line 3—3 of Figure 1.

Figure 4 is an end elevation of my invention. In practicing my invention I employ a housing 5 equipped with a removable cover 6 and fashioned with front, rear and bottom walls 7, 8 and 9 respectively.

Positioned on the bottom wall 9 adjacent the front wall 7 is a water tank 10 connected to a water pump 11 by any suitable means, for instance a copper coil 12. Said water pump is provided with a driven shaft equipped with a driven pulley 13 connected to a drive pulley 13a fixed on a drive shaft 14 of a fan motor 15 whereby said water pump 11 is driven. The fan motor 15 is mounted within an air conduit 16 secured about an air inlet 17 formed in the rear wall 8.

A suitable bracket 18 supports said fan motor within said conduit. A screen 19 covers the opening 17 and serves to screen air passing therethrough. The drive shaft 14 has fixed thereto between the pulley 13a and the motor 15 a fan 20 equipped with the usual blades.

An ice tank 21 is located above the water tank 10 and is fashioned with inner and outer walls forming a water jacket 22. Said ice tank and water jacket are supported above the water tank by horizontally extending support brackets 23.

Located in front of the air conduit 16 is a radiator 24 having upper and lower sections 25 and 26 respectively, the lower section being connected to the pump 11 by means of a pipe 27

while the upper section 25 is connected to the water jacket 22 by means of a pipe 28. A suitable core connects the upper and lower sections 25 and 26 together.

Secured in front of the water jacket 22 by means of a bracket 29 is a transversely extending trough 30 having angularly disposed sides and a perforated bottom to which is secured a depending section of wire mesh 31 extending into the upper section of the water tank 10. The upper section of the water jacket 22 is provided with a discharge pipe 32 having a downwardly extending section terminating above and over the trough 30. The front wall of the housing is formed with an aperture 33 over which is provided a screen 34 whereby air discharged therethrough is screened.

The lower section of the water tank 10 is provided with an outlet faucet 35 connected thereto through the front wall 7 as clearly illustrated in Figure 2.

In operation, the water tank 10, radiator 24 and water jacket 22 are filled with water or other suitable liquid and the ice tank 21 filled with ice or other suitable refrigerant. The motor 15 is then operated causing the pump 11 to circulate water from the water tank 10 upwardly through the radiator 24 and discharging the same into the water jacket 22. The ice within the ice tank serves to cool the water circulating in the water jacket and said water is discharged into the trough through pipe 32. Upon discharge of the water in the trough 30 the same flows through the perforations over the screen 31 into the water tank 10.

During the operation of the motor 15 the fan serves to circulate air through the radiator and through the screen of water flowing over the screen 31 and thereby discharges cool air through the aperture 33 in the front wall of the housing.

7. The water tank 21 is formed with a discharge vent 36 extending through the jacket whereby water from melted ice is discharged into the water tank 10.

In instances where it is desirable to connect the apparatus to a supply of water under pressure, for instance a city water line, the coil 12 may be disconnected from the pump 11 and a connection 40, as illustrated in dotted lines in Figure 1, utilized for connecting the pump directly to the city water line. In instances of this character the discharge faucet 35 is open to permit the water from the tank 10 to be discharged therefrom to prevent the same from overflowing.

into the housing about the pump and other units therein.

From the foregoing it will be apparent that I have provided an air conditioning apparatus composed of a minimum number of parts so arranged and connected as to form a compact unitary structure. Furthermore, the upper and lower sections 25 and 26 of the radiator are disposed above and below the upper and lower walls 10 of the air conduit 16 respectively whereby the air is forced through the core of the radiator, also, the bottom of the tank 21 is located out of the path of the air forced through the core.

What I claim is:

15. 1. A device of the character described, comprising, a housing, an ice tank arranged within the upper portion of said housing and fashioned with a water jacket, said housing fashioned with an air inlet conduit at one end and with a discharge opening at the other end, a water tank within said housing subjacent said ice tank, a pump connected to said water tank, a radiator arranged in front of said air inlet conduit and connected to said water jacket and said pump, a 20 fan and a driving motor therefor arranged within said air inlet conduit for circulating air through said radiator and said motor operating said pump, a trough connected to said water jacket, means communicating with said water jacket for discharging water in said trough, and

a screen suspended from said trough for receiving water discharged from said trough in a manner whereby the air circulated through said radiator is circulated through said screen for discharge through said outlet opening.

2. A device of the character described, comprising, a housing, an ice tank arranged within the upper portion of said housing and fashioned with a water jacket, said housing fashioned with an air inlet conduit at one end and with a discharge opening at the other end, a water tank within said housing subjacent said ice tank, a pump connected to said water tank, a radiator arranged in front of said air inlet conduit and connected to said water jacket and said pump, a 15 fan and a driving motor therefor arranged within said air inlet conduit for circulating air through said radiator and said motor operating said pump, a trough connected to said water jacket, means communicating with said water jacket for discharging water in said trough, a screen suspended from said trough for receiving water discharged from said trough in a manner whereby the air circulated through said radiator is circulated through said screen for discharge 20 through said outlet opening, and means connectable to said pump for supplying water thereto independent of said water tank.

FRANK C. SEEGER. 30
